CRIBBAGE BOARD

William F. Swift, Vineyard Haven, Mass.

Application June 17, 1946, Serial No. 677,213

1 Claim. (Cl. 235—90)

1

This invention relates to a cribbage board which by its peculiar structure will indicate that a player has traversed one full round of holes in the playing of the game of cribbage.

An object of the invention is to provide a cribbage board having incorporated therein manually operated means for indicating that a round of holes has been traversed in the playing of the game.

Another object of the invention is to provide a cribbage board that includes indicating means that is simple in operation, durable in use and for the purpose designed is inexpensive to manufacture.

With the above and other objects in view, the invention consists of the novel details of construction, arrangement and combination of parts more fully hereinafter described, claimed and illustrated in the accompanying drawing in which:

Figure 1 is a top plan view of a board embodying the invention;

Figure 2 is a side view thereof;

Figure 3 is an end view partly in section;

Figure 4 is a view of the opposite end and

Figure 5 is a sectional view on the line 5—5 of Figure 1.

Referring more in detail to the drawing, the reference numeral 10 designates a cribbage board constructed in accordance with the invention, which is of conventional shape and size and provided with the apertured playing surface 12.

One end of the board is provided with a cavity 14 for retaining the pegs therein when the game is not being played, and the cavity is closed by the cover 16 pivotally mounted thereof by means of the screw 18.

Underlying the first five apertures in the inner rows on the playing surface 12 is a cavity 20, and extending transversely of this cavity is a pin 22 which by means of depending apertured ears 24 formed thereon pivotally mounts the levers 26 in parallel spaced relation with each other on the pin 22. Each of these levers is mounted off center, and resting on the short end 28 thereof is the enlarged head 30 of the pin 32 vertically mounted in the bore 34 at the end of the inner rows in the playing surface. The long end 36 underlies the first five apertures of the playing field, and when a tallying peg 38 is inserted in either of these apertures, the long end of the lever is depressed, and the short end raised so that the pin 32 will rise above the playing surface. The bore fits the pin loosely enough for movement therein, but tight enough to retain the

2

pin in raised position when moved upwardly by the lever. Applicant's board 10 provides sixty playing holes for each player, and each player makes a double round for one hundred and twenty holes for a game which is conventional for cribbage boards. Thus the last hole to be used by any one player is the last hole on the inside row of the pairs of holes used by the single player. Applicant underlies the last five holes of each row with the levers 26 so that when a player moves down the inside row of holes on his first round, the five holes in this row can be used, should his count end in any one of the five holes, rather than just one hole. For example, if, in playing the game, the player should land in hole 47, at the end of the hand, then when a crib is picked up, it is found to contain a count of 10 or 12. This would land the player at hole 57 or 59. Thus the lever would be actuated in either case. However, should the lever only underlie the end hole, the lever would not be actuated. Then when a new hand is pegged, the first count usually being over one, the hole 60 would be by-passed, and a lever underlying only one hole would not be actuated. The five holes, therefore, give the player a good range and a good chance of landing in either of the five holes during his first round. The board, therefore, is used to signify when the first round has been completed, and not when a game is won.

Thus a cribbage board has been provided which will indicate to the players when one round has been completed during the playing of the game. Since both of the pins are below the playing surface when the game starts, and as the game progresses, the tallying pegs will raise the pins when the second row of apertures is used.

It is believed that the operation and construction of the invention will be apparent to those skilled in the art, and it is to be understood that changes in the minor details of construction may be resorted to provided they fall within the spirit of the invention and the scope of the appended claim.

Having thus described the invention, what is claimed as new and desired to be secured by Letters Patent is:

In a cribbage board, the combination which comprises an elongated rectangular game board having spaced pairs of rows of tally pin receiving openings positioned in sections of five in each row in the upper surface and having an elongated centrally positioned opening extended inwardly from the starting end of the board, said elongated opening extended under the openings of

55

the inner rows of the end section, said board also having a pair of round indicating pin openings spaced from the last pin of the inner rows of the end section, round indicating pins with heads on the inner ends frictionally mounted in the said round indicating pin openings, levers pivotally mounted in the said elongated opening at points positioned between the said round indicating pin openings and the last tally pin opening of each of the inner rows, said pivotal mountings spaced from one of the ends of the levers providing long and short ends with the short end of each of said levers extended under the said round indicating pins and the long ends extended under the five tally pin openings in the end section of the board whereby a tally pin ex-

tended through one of said five openings therefor actuates the lever on that side of the board to elevate the round indicating pin positioned above the short end thereof.
